UNITED STATES PATENT OFFICE

JAMES H. CHRISTIAN, OF DETROIT, MICHIGAN.

DESIGN FOR A TIRE-CASING.

47,947.

Specification for Design.

Patented Oct. 12, 1915.

Application filed June 28, 1915. Serial No. 36,873. Term of patent 14 years.

To all whom it may concern:

Be it known that I, JAMES H. CHRISTIAN, a citizen of the United States of America, residing at Detroit, in the county of Wayne and State of Michigan, have invented a new, original, and ornamental Design for a Tire-Casing, of which the following is a specification, reference being had herein to the accompanying drawing, forming part thereof.

In the drawings, Figure 1 is a view of a face of a tire casing showing the new de-

sign; Fig. 2 is a view in cross section through the tire casing.

I claim:

The ornamental design for a tire casing as shown.

In testimony whereof I affix my signature in presence of two witnesses.

JAMES H. CHRISTIAN.
